UNITED STATES PATENT OFFICE.

ARTHUR HAZELDINE BURT, OF MOSMAN, NEAR SYDNEY, AND HENSHAW JACKSON AND CHARLES ALLT FINCH, OF SYDNEY, NEW SOUTH WALES, AUSTRALIA.

EXTRACTION OF GREASE FROM WOOL.

No. 829,764.

Specification of Letters Patent.

Patented Aug. 28, 1906.

Application filed December 8, 1905, Serial No. 290,987.

To all whom it may concern:

Be it known that we, ARTHUR HAZELDINE BURT, residing at Mosman, near Sydney, HENSHAW JACKSON, residing in O'Connell street, Sydney, and CHARLES ALLT FINCH, residing in Elizabeth street, Sydney, in the State of New South Wales, Commonwealth of Australia, subjects of the King of Great Britain and Ireland, have invented new and useful Improvements in the Extraction of Grease from Wool, of which the following is a specification.

Our invention consists in the obtaining of wool-grease from sheep's wool by means of volatile solvents, such as benzene, without opening the bales or packs in which such wool is made up for transportation.

The extraction of wool-fat from baled wool without opening the packs is of much importance commercially, because by operating on it while contained in the unbroken packs the extraction may be effected at any convenient place during transit. It would be manifestly impossible to effect the extraction at the place of production of the wool, because the expense of operating a number of independent plants suitable for the purpose would involve prohibitive cost. The packs operate as filters which retain the greater portion of solid and non-soluble matter and are themselves freed of grease and rendered fit for reuse with scoured wool. The problem of obtaining wool-fat in large quantities at a marketable price depends for its solution not upon the technical efficiency, but rather upon the economical operation of the process used. The breaking of the bales no less than the treatment of relatively small quantities of wool at individual places of production would entail a cost which would make the value of the product too high to enable it to be sold in competition with other fats for which it may be substituted for manufacturing purposes.

According to our method the extraction is effected on a large and economical scale at shipping centers or rail junctions where large quantities of wool are handled without involving any change or serious delay in forwarding arrangements. Coincidentally a reduction is made in the gross weight of the bale, and a consequent saving in freight thereon is effected.

In carrying out our invention we use a connected series of apparatus in which the solvent is protected against atmospheric vaporization during the several steps of the process and is recovered for reuse and is reused continuously.

In this apparatus the wool is placed in a close press-chamber provided with a piston or lifting false bottom operated by a ram which is worked by hydraulic or other power. A body of solvent liquid is introduced into this press-chamber as soon as the same has been closed. To insure complete penetration of the solvent into the heart of the bale, inspirating-needles (with button-heads to facilitate insertion and withdrawal) are driven downward into the bales. Complete saturation of the wool in the bale is effected by submitting the same to a number of successive compressions by reciprocating the piston, whereby the solvent is alternately squeezed out of and allowed to resoak the wool. The fat-charged solvent after withdrawal from the press-chamber is run through a filter in which wool may be used for a filter-bed, and the filtered liquid is thence conveyed to a still, wherein the volatile liquid is driven off to a condenser fitted with an air-pump, and is thence returned to the solvent-tank for reuse. After final pressing in the press-chamber to squeeze out the free liquor the wool is lifted into a closed drying-box, through which a draft of air is pumped or drawn by vacuum. This air takes up the absorbed solvent and carries it through the condenser in which it is extracted and whence it passes to the solvent-tank.

The semisolid residue in the still is treated by pressure and otherwise for the purification of the wool-fat according to known processes.

The piping and valve arrangements are so disposed that the same charge of solvent may at will be reused for two or more bales successively, or so that a second (rinse) charge of fresh solvent may be applied so as to more completely dissolve out the fat.

The press-chamber may be provided with an intermediate grating to sustain the top of the bale while pressure is applied to it below by means of the piston to effect the solution of the grease by regurgitating the solvent through the wool.

In the annexed drawings, Figure 1 is a dia-
grammatic figure explanatory of the general
arrangement of the several parts of the appa-
ratus; Fig. 2, a vertical section through the
5 press-chamber; Fig. 3, a top plan; Fig. 4, a
horizontal section through upper part of same
on line $x x$; Fig. 5, a similar horizontal section
through lower part of same on line $t t$; Fig.
6, a sectional horizontal plan on line $u u$. Fig.
7 is a side elevation of the press-chamber; Fig.
8, a detailed fragmental view showing section
of piston; Fig. 9, a plan of the piston, and Fig.
10 an elevation showing the inspirator-needle.

Referring to Fig. 1 in the annexed sheet of
explanatory drawings, A is the press-cham-
ber; B, the ram-cylinder; C, the filter-box,
and D a series of two or more drying-cham-
bers. E is the air-heater; F, the still; G, the
condenser; K, air-pump; L, solvent-tank;
M, auxiliary solvent tank; N, the solvent-
pump; O, vacuum-cylinder, and P grease-
tank. If it be found convenient to place the
condenser G and the solvent-tank L above
the level of the press-chamber A, the solvent
25 may be allowed to flow by gravity, in which
case the solvent-pump may be dispensed
with; but it is generally preferred to adopt
the arrangement in which the solvent is
moved positively by the pump N. The
30 solvent is supplied from the pump N to the
press-chamber A through the pipe a . The
solvent-pump N draws its supply of solvent
from the tank L through the pipe l . The
solvent-pump N has also a connection
35 through the pipe m with the auxiliary sol-
vent-tank M, into which grease-laden solvent
from the press-chamber A passes by
the pipe o . $z z$ represent valves in the pipes.
The bottom end of the press-chamber A is
40 connected by the pipe c to the filter C, which
may be made to act either upwardly or
downwardly.

f is a pipe for delivering filtered grease-
laden solvent from the filter C to the still f ,
45 which latter is heated by a coil supplied with
superheated steam.

g is a by-pass connection between the filter
C and the pipe l , and j a pipe connection be-
50 tween the auxiliary tank M and the still F.
The vaporized solvent passes by the pipe p
to the condenser G. There are also pipe
connections d from the several drying-boxes
55 D to the pipe connection p between the still
F and the condenser G. These drying-
boxes have each a valve in the head through
which atmospheric air may be admitted to
them, and they are also provided with pipe-
services e to convey heated air from the air-
heater E, which is warmed by a steam-coil.
60 The mixed air and the condensed vapor
which pass from the condenser G enter the
vacuum-reservoir O and thence pass to the
air-pump K, which delivers the same to the
air-heater E through the pipe k or to waste
65 through the outlet N. The solvent con-

densed in the condenser G passes by the
pipe r (which is fitted with a non-return
valve) to the solvent-tank L, whence it is
conveyed, as before stated, by the pipe l to
the force-pump N, and thence for reuse to
70 the press-chamber A. The one charge of
solvent may be used repeatedly, if desired,
by leaving it in the press-chamber until it
becomes fully charged with grease by re-
peated treatment of successive bales of wool. 75

It will be observed that by operating the
valves Z the same charge of solvent can be
circulated through the press-chamber A and
the filter C as often as may be found neces-
sary and finally run into the still F through
80 the pipe f , or, at the option of the operator,
the first charge of solvent laden with grease
may be run into the still F from the filter C
through the pipe f and a rinse charge of
85 fresh solvent then circulated by means of
the pump N through the wool in the press-
chamber A, and thence to the auxiliary sol-
vent-tank M through the pipe o , whence it
may be drawn through the pipe m to the
pump N and used on another bale of wool in
90 the press-chamber A.

The form of the press-chamber which we
use in practice is shown in Figs. 2 to 9. It
consists of two chambers superposed, of
which the upper one 1 is of less area than the
95 lower one 2, but in alinement therewith at
the corners, so that the corner parts will
form a continuous guide for the plunger or
piston 3 throughout its stroke. This piston
is covered on the face with grating-bars 4 100
and is fitted with two or more spring-sus-
tained drop-valves 5, whose heads rise above
the face of the grating-pieces 4, the object
being that these valves shall be forced open
by contact against the lower side of the bale
105 of wool which is dropped into the chamber.
The piston 3 is carried on a ram or rod 6, in
the upper side of whose stuffing-box 7 a
water-well 8 is formed to check escape of the
volatile solvent through the packing. The
110 piston is guided at its four corners by direct
contact with the interior surface of the cor-
ners of the chambers, and it is provided with
a leather lip-packing 9, carried by a junk-
ring 10. This packing makes a vapor-re-
115 taining joint in the upper section 2 of the
chamber, but leaves a gap at the four sides
of the piston when the same is in the lower
section 1 of the chamber. The top closure
120 is a reinforced cap-plate 11 with a perforated
false lining 12, the perforations being pro-
vided to allow free access and exit of solvent
to and from all parts of the upper surface of
the bale when it is under compression by the
piston. The solvent-supply pipe a conveys
125 the solvent to the cavity between the false
plate 12 and the head 11. The head is se-
cured, preferably, by pivot-bolts 13, whose
wing-nuts take against lugs 14 on the head.
130 15 is a ring-pump leather inserted in an an-

nular cavity below the joint 16 to make said joint liquor and vapor tight.

Intermediate of the upper and lower chambers 1 and 2 is a divisional grating 17, which 5 may be formed of slotted or drilled plate, adapted to run in a carrier-guide 18. This plate 17 is manipulated by a spindle 19, which is carried through a stuffing-box 20 and is operated by a hand-screw 21 or by 10 other suitable means.

The inspirating-needles shown in Fig. 10 are tubular stems formed with sharp points. They are perforated at many points with fine holes to permit flow of solvent through 15 them into the wool and conversely exit of greasy solution. Button-heads through which the bore is continued are fitted to these needles to facilitate their insertion and withdrawal.

20 In operation the rack-plate 17 being re-tired the bale of wool is dropped into the press-chamber and the head 11 closed down. Solvent is then run through the pipe *a*, completely immersing the bale and soaking the 25 same by direct absorption through its exterior surface and also through the inspirating-needles, which are driven into it from the top end before it is inserted into the press-chamber. The piston 3 being drawn down to the 30 lower end of the chamber and the grating 17 closed in over the top of the bale, which is now completely submerged in the solvent liquor, pressure is applied to the ram 6 two or three times or oftener, so as to cause the 35 solvent to surge through the wool in the bale and dissolve the wool-fat contained therein. Finally, the grating 17 is retired and the bale is put under pressure against the head 11 in order to squeeze out the free solvent. The 40 solvent is run off through the pipe *c* either to the filter *C* or to the auxiliary solvent-reservoir *M*. The head 11 is now removed and the bale raised up by exerting pressure on the ram 6 and lifted into one of the drying 45 boxes *D*, which is closed down on it, and the hot-air *e* and exhaust *d* services opened. The remaining solvent is thus evaporated out of the bale and recondensed in the still *G* for reuse. The inspirating-needles are not with- 50 drawn until after the dried-out bale is taken from the drying-box, as they serve to convey air into and vapor out of the bale.

The provision of the intermediate grating 17 and accessory parts is not essential, as it 55 is practicable to press the bale directly against the false head 12, provided that the solvent has freedom to surge past the piston. The leather packing-ring of the piston is pro- vided only to prevent vaporization of solvent

when the piston is raised up near the top of 60 the chamber and the head 11 opened while the bale is being inserted and lifted out.

The leather packing does not fill the clearance between the sides of the chamber 2, and the piston and the solvent is therefore free to 65 surge past the piston during the operation of repeatedly compressing the wool and relieving the pressure thereon to effect solution of the grease by regurgitating the solvent through the wool. When a press-chamber 70 of identical form throughout its length is used and the wool pressed directly against the head of the chamber, the leather packing must be made sufficiently flexible to permit the solvent to flow past it to and from the 75 space below the piston, while when there is no pressure it must close up to the chamber-walls to prevent vaporization of the solvent contained in the chamber. The automatic valves 5 are kept open by the weight of the 80 wool thereon, but when the wool is lifted out of the press they are closed by their supporting-springs, and thus seal the space below the piston and prevent loss of solvent by evaporation.

85 Novelty is not claimed for the distillation of the filtrate to separate the grease and recover the solvent nor for the recovery of the absorbed solvent by treatment with hot air.

It may also be said that no novelty, 90 broadly, is claimed for the extraction of grease or oil from substances contained in bags or wraps by pressure of the package or bale.

What we claim as our invention, and desire 95 to secure by Letters Patent, is—

The herein-described method of extracting the fat from wool by means of liquid, volatile solvents, which consists in immersing an unopened transportation pack or bale of wool 100 in the solvent, then alternately and repeatedly pressing said pack and allowing it to expand by its own resiliency, thereby causing the solvent to flow repeatedly through the wool in the pack, then removing the pack 105 from the solvent and placing it in a closed chamber, and then forcing air through said chamber in order to take up and remove the volatile solvent from the pack.

In testimony whereof we have signed our 110 names to this specification in the presence of two subscribing witnesses.
